G. R. MARSICO,

SIGNAL,

APPLICATION FILED JUNE 9, 1919. RENEWED AUG. 27, 1921.

1,393,896.

Patented Oct. 18, 1921.

UNITED STATES PATENT OFFICE.

GERARD R. MARSICO, OF BROOKLYN, NEW YORK, ASSIGNOR TO PURITON MANUFACTURING CORPORATION, OF BROOKLYN, NEW YORK, A CORPORATION OF NEW YORK.

SIGNAL.

1,393,896.

Specification of Letters Patent.

Patented Oct. 18, 1921.

Application filed June 9, 1919, Serial No. 302,739. Renewed August 27, 1921. Serial No. 496,161.

To all whom it may concern:

Be it known that I, GERARD R. MARSICO, citizen of the United States, and resident of Brooklyn, in the county of Kings and State 5 of New York, have invented certain new and useful Signals, of which the following is a specification.

This invention relates to signals and more particularly to an improved construction of 10 the form of my invention shown in my application Serial No. 242,445, filed June 28, 1918, and to a further development of the invention disclosed in a co-pending application executed by me May 22, 1919, Serial 15 No. 302,740.

In my application No. 242,445, filed June 28, 1918, I provided a structure for augmenting the force of a rotor against a vibratory member so as to produce loud sound 20 having lasting qualities, effectuating or accomplishing such end by an arrangement of clutch devices adapted to be thrown into operative engagement with the rotor and to be subsequently released from such engagement 25 to permit the rotor to revolve freely. For the purpose of further increasing this action of the parts I have shown and described in my application executed May 22, 1919, a plurality of sliding clutch devices 30 adapted when in one position to engage at diametrically points with the rotor and to entirely disengage therefrom when in a second position, the latter position serving to eliminate friction between the rotor and the 35 clutch devices while permitting the first performance of said clutch devices to exert maximum leverage action against said rotor.

In the construction which I will describe presently I utilize in a positive manner the 40 action of a revolving support to move an eccentric, the ring of which being provided with an integral clutch device adapted when in an inactive position to be disposed relatively to the clutch surface of a rotor so as 45 not to retard the movement thereof, a second position of the clutch device under the action of the eccentric promptly operating to become a temporary fixed part of the rotor so that the two rotate together. I have followed 50 the same idea of an annular internal clutch surface on a rotor; positioning the same at or near the periphery of the rotor

to take full advantage of the leverage action of the clutch device therewith, and I have employed correspondingly the same 55 principle of supporting the rotor for movement independent of the clutch device.

In the present embodiment of the invention I also look to the compactness and simplicity of the device, employing an exceedingly small number of parts; associating the same to warrant positive operation thereof at the requisite time and establishing the mechanism as a whole which can be manufactured at a comparatively small cost. 60 65

The various important features of my invention will be particularly pointed out hereinafter in connection with a detailed description which I have selected for illustration in the accompanying drawings, in 70 which similar reference characters indicate corresponding parts in the several views.

In the drawings,

Figure 1 is a side view of the signal showing parts broken away. 75

Fig. 2 is a side view of the rotor.

Fig. 3 is a side view of the combined guide and stop disk.

Fig. 4 is a side view of the eccentric showing the ring and disk separated. 80

Fig. 5 is a perspective view of the rotary support.

Fig. 6 is a side view of the rotor showing a slightly modified form of the invention.

10 represents a case provided with a resonator 11 and vibratory member 12, the latter having an anvil 13 adapted to co-act with a striking surface 14 of a rotor 15. 85

The rotor is mounted to revolve freely on a cylindrical extension 16 of a rotary support 17 which is freely arranged on a fixed axle 18 carried by a bracket structure 19. The bracket structure is arranged in the case 10 in any well known suitable manner and it carries a guide 20 having a sliding plunger 21. This plunger has teeth 22 meshing with a gear wheel 23, the latter mounted upon a shaft 24 carried by the bracket structure 19. This shaft also supports a gear wheel 25 which meshes with a pinion 26 which constitutes a fixed part of the rotary support 17. In this manner power will be transmitted to said rotary support when the plunger 21 is actuated. 90 95 100

The rotary support has an extension 27 of substantially rectangular form and said extension is fixed in a corresponding opening 28 formed at the center of a combined guide 5 and stop disk 29. While it will be observed that the rotor is free for movement independent of the rotary support 17 it will likewise appear that said disk 29 remains always fixed. On the extension 27 at a point 10 between the rotor 15 and said disk 29 is an eccentric 30 consisting of a disk 31 fixed to said extension and a ring 32 embracing said disk and provided with a fixed clutch device 33. This device has an effective gripping 15 surface 34 adapted to engage with the annular internal clutch surface 35 of the rotor. A spring 36 is employed for normally holding the plunger elevated. The disk 29 carries a suitable guide 37 which accommodates 20 the clutch device 33 in its movements while holding the same normally to one side of a perpendicular line drawn through the center of the rotor. The ring 32 is positioned to engage with a stop 39 on the disk 29 25 which prevents retrograde action of the clutch device. It also limits the movement of the surface 34 of the clutch device with respect to the annular clutch surface 35 of the rotor.

30 When pressing the plunger downward motion is conveyed to the eccentric to raise the high side of the disk 31 with respect to the horizontal center of the rotor and in consequence thereof the surface 34 of 35 the clutch device is moved into firm gripping engagement with the annular surface 35 of the rotor, temporarily locking or securing the two parts together and thus causing effective actuation of the striking surface of the rotor against the anvil of the 40 diaphragm. The force of the leverage action is considerable and the pulsations induced in the diaphragm give life to sound of great amplitude and intensity. When the 45 plunger returns to its normal position, the eccentric does likewise, again restoring the relative inactive positions of the surfaces 34 and 35 to permit the applied power contributed to the rotor to cause the latter to 50 freely revolve by inertia.

In the modified form of the invention shown in Fig. 6 the eccentric consists of a disk 39 having a flat side 40. The ring 41 is provided with a corresponding flat side 55 42 adapted to co-act with the side 40 to form a stop to limit the movement of the clutch device 33 in an annular direction.

While I have herein shown and described and have pointed out in the appended claims 60 certain novel features of construction, arrangement and operation which characterize my invention, it will be understood by those skilled in the art that various omissions, substitutions, and changes in the forms, proportions, sizes, and details of the device, of

the materials used, and of their operations may be made without departing from my invention.

What I claim as new is:

1. A device of the class described comprising a vibratory member, a rotor co-acting with said member to rotate the same, means for supporting the rotor for free rotation, a driven guide and stop member, an eccentric movable with said stop and guide member and adapted for rectilinear movement thereon, means for stopping rotation of the ring of the eccentric, a clutch device carried by the ring of the eccentric, and a clutch surface formed on the rotor and adapted to co-act with said clutch device on one position of the eccentric and thereby cause the rotor and said clutch device to revolve together. 70 75 80

2. A device of the class described comprising a vibratory member, a rotor co-acting with said member to vibrate the same, said rotor having an annular clutch surface, a fixed axle, a support mounted to revolve on said axle, the rotor mounted on the support to revolve independently thereof, an eccentric carried by the support and provided with a clutch device adapted to engage with the clutch surface to cause said clutch device and the rotor to revolve together when the eccentric is in one position, and a member fixed to the support and forming a guide for said clutch device. 85 90 95

3. A device of the class described comprising a vibratory member, a rotor co-acting with said member to vibrate the same, said rotor having an annular clutch surface, a fixed axle, a support mounted to revolve on said axle, the rotor mounted on the support to revolve independently thereof, an eccentric carried by the support and provided with a clutch device adapted to engage with the clutch surface to cause said clutch device and the rotor to revolve together when the eccentric is in one position, and a member fixed to the support and forming a guide for said clutch device, and a stop portion on the guide member for limiting rotation of the eccentric. 100 105 110

4. In a device of the class described the combination with a rotor having an internal annular clutch surface, means supporting the rotor for free rotation and a vibratory member adapted to co-act with the rotor, of an eccentric having a clutch device adapted to co-act with the clutch surface of the rotor, and means for actuating the eccentric to revolve the rotor. 115 120

5. The combination with a vibratory member and co-acting rotor, the rotor having an internal annular clutch surface, means supporting the rotor for free rotation, an eccentric for positively driving the rotor and including a clutch operable to respectively engage with and disengage from 125 130

the annular clutch surface, means for operating the eccentric, a stop for limiting rotation of the ring of the eccentric, and a guide for said clutch device.

5 6. In combination with a vibratory member and co-acting rotor, the rotor supported for free rotation and provided with an internal annular clutch surface, an eccentric including a clutch device movable respectively

into and out of engagement with the clutch 10 surface, of means for actuating the eccentric, and a disk movable with the eccentric and having a stop for limiting rotation thereof and a guide for said clutch device.

Signed at Brooklyn, in the county of 15 Kings and State of New York, this 29th day of May, A. D. 1919.

GERARD R. MARSICO.
